(57) CLAIM

The ornamental design for a bridge pressure sensor, as shown and described.

DESCRIPTION

FIG. 1 is an isometric view of an embodiment of the bridge pressure sensor;

FIG. 2 is a top view of the embodiment shown in FIG. 1; FIG. 3 is a right side view of the embodiment shown in FIG. 1 (the left side is similar but opposite hand);

FIG. 4 is a front view of the embodiment shown in FIG. 1; FIG. 5 is a rear view of the embodiment shown in FIG. 1; FIG. 6 is a bottom view of the embodiment shown in FIG. 1;

FIG. 7 is an isometric view of another embodiment of the bridge pressure sensor;

FIG. 8 is a top view of the embodiment shown in FIG. 7; FIG. 9 is a right side view of the embodiment shown in FIG. 7 (the left side is similar but opposite hand);

FIG. 10 is a front view of the embodiment shown in FIG. 7; FIG. 11 is a rear view of the embodiment shown in FIG. 7; and, FIG. 12 is a bottom view of the embodiment shown in FIG. 7.
